UNITED STATES PATENT OFFICE

BART E. SCANLAN, OF OMAHA, NEBRASKA

ROTARY BRUSH

Application filed April 2, 1929. Serial No. 351,932.

This invention relates to rotary brushes and an object of the invention is to provide for rotating a brush in a fixed handle for the purpose of cleaning strainers, graters, salt and pepper shakers, combs, filters or any 5 foraminous material.

Further objects of the invention are to provide a device of the character referred to which is strong, durable, thoroughly reliable 10 for its intended purpose, very simple in its method of assembly, and comparatively inexpensive to manufacture and operate.

With the foregoing and other objects in view, the invention consists of a novel construction, combination and arrangement of parts, as will be hereinafter more specifically described and illustrated in the accompanying parts, wherein is disclosed an embodiment of the invention, but it is to be understood that changes, variations and modifications may be resorted to without departing 15 from the spirit of the claim hereunto appended.

In the drawings wherein like reference 20 characters denote corresponding parts throughout the several views:

Figure 1 is a side elevation of the brush in accordance with this invention.

Figure 2 is a longitudinal and detailed sectional view thereof, and

Figure 3 is a central longitudinal, broken away section through the handle thereof.

Referring to the drawings in detail, 5 indicates an elongated solid handle formed 35 of any desired material. While the configuration of the handle is shown to be frustoconical, the shape thereof may be changed as desired without departing from the spirit of the invention. Extending inwardly from 40 one end of the handle is a socket 6 which extends along the longitudinal median for a portion of the length of the handle and terminates at its inner end in a transverse sectional opening 7 extending entirely through 45 the handle 5.

Rotatably mounted in the socket 6 is a tubular sleeve 18 having the interior walls at one end thereof provided with a peripheral thread 9 for threadably supporting the 50 shank 10 of a screw. The screw has an en-

larged head 11 projecting outwardly from the inner end of the sleeve of larger diameter than the socket 6 which head projects into the transverse opening 7 to prevent axial movement of the sleeve 18. A shaft indicated generally at 12 has the inner end 13 anchored in the other end of the tubular sleeve 18 by means of solder 14 or other suitable material. 55

The shaft 12 is preferably formed of metal 60 of such strength as to give the desired rigidity to the brush. The shaft 12 is formed of a pair of strands 15, 16 spirally wound about each other and having bristles anchored 65 between the windings and projecting radially from the shaft 12.

The bristles 17 may be of such quality as will be necessary and the configuration of the outer surface of the bristles 17 is preferably 70 of cylindrical shape.

In the assembly of the brush in accordance with this invention, the shaft 12 and the bristles may be formed in one operation, the sleeve 18 and the handle 5 formed in another operation whereupon the shaft may be soldered within one end of the sleeve 18 and 75 very simply and easily assembled in the handle 5.

Having thus described my invention, what I claim as new is:

In a device of the character described, a handle, having a bearing socket extending from one end of the handle inwardly, said handle formed with a transversely extending opening at the inner end of the socket 80 and communicating with said socket, a tubular sleeve rotatably mounted in the socket, means on the inner end of the sleeve flaring outwardly to the transverse opening to prevent axial movement thereof, a shaft anchored in the outer end of said sleeve and projecting forwardly thereof and bristles anchored in the shaft to provide an abrading surface, said means consisting of a screw 85 threadedly engaging the inner end of the sleeve and the head thereof confined in the transverse opening.

In testimony whereof I affix my signature.

BART E. SCANLAN. 100
